UNITED STATES PATENT OFFICE.

WILLIAM O. BRYANT, OF LOS ANGELES, CALIFORNIA, ASSIGNOR TO UNDERWOOD TYPEWRITER COMPANY, OF NEW YORK, N. Y., A CORPORATION OF DELAWARE.

TYPEWRITING MACHINE.

Application filed January 28, 1925. Serial No. 5,261.

This invention relates to clips for positioning work-sheets in typewriting machines, and one of its features is the provision of means for holding a card in front of the 5 platen of the machine upon which it is desired to type a line of data.

Another feature is the provision of means whereby the line of typing upon the face of the card is recorded upon a copy-sheet 10 around the platen.

Another feature relates to the design of the clips, and to the means of attaching the same to an Underwood standard machine. The clips may be readily slipped onto or 15 off the machine, which requires no alteration thereof, and are made interchangeable to fit the existing machines.

A copy-sheet having a superimposed narrower sheet of carbon-paper is inserted in 20 the machine down a rear table at the introductory side of the platen and under the platen engaging co-operating feed-rolls and up in front of the platen. A card upon which it is desired to type a line is then 25 inserted bottom edge first in front of the platen, between the platen and the clips, and down to a locating stop below the printing line. The clips, which are made of resilient material, are sprung onto the feed-roll shaft, 30 and are bent inwardly against the platen to render them effective to firmly hold the card against the platen in a flat condition.

A line of typing is then written upon the card and is consequently copied on the copy- 35 sheet. The card is removed by gripping the leading edge with the fingers and the copy-sheet is line-spaced, so that, when a fresh card is inserted again in the machine, the line typed upon the card will be recorded 40 on the copy sheet as a record line of typing thereon. It will be noted that the work-sheet, as it is designed and shown in the drawings, consists of a card upon which it is desired to type a line of data pertaining 45 to the monthly billing of a gas company. In such cases it is customary to fill in the name and address on the card by mechanical means previous to inserting the card in the typewriting machine. It is also customary 50 for the gas company to send their customers bills having detachable stubs which each customer returns when making payment, to identify the transaction. While it is convenient to type the total amount of the bill

upon the stub, it is not desirable to have it 55 written twice upon the copy-sheet. To this end, the sheet of carbon-paper is narrower than the card, so that the total amount typed on the stub will not be transferred or copied upon the copy-sheet. 60

It is sometimes desired to type two lines upon the card, and, although no special mechanism is provided for so doing, the method will be briefly stated. The card is held firmly against the platen with one hand, 65 while the platen is spaced one line either by means of the finger-wheel or the regular line-spacing mechanism; thus the card, the copy-sheet and the carbon-paper thereinbetween are simultaneously line-spaced. 70

Other features and advantages will hereinafter appear.

In the accompanying drawings,

Figure 1 is a front view in elevation of 75 part of an Underwood typewriting machine showing the platen, the feed-rolls and the clips attached thereto. It also illustrates the relative position of the card, the carbon-paper and the copy-sheet.

Figure 2 is a cross-sectional view in elevation through the line 2—2 of Figure 1, and shows the position of the clips in relation to the platen when holding the upstanding card in front thereof.

Figure 3 is a side view in elevation of one 85 of the clips, and shows the clip both in its normal or released position and when sprung on the machine under tension.

Figure 4 is a perspective view of one of 90 the clips.

Figure 5 shows one of the forms or cards that may be used in connection with this device.

A copy-sheet 10 having a superimposed carbon-sheet 11 is inserted, leading edge 95 first, down a rear table 12 and under a platen 13 co-operating with feed-rolls 14 and 15 and up in front of said platen. The feed-rolls 14 and 15 are operatively mounted on a shaft 16 connecting the two platen frames 17 and 18 upon which the platen is journaled by means of the axle 19 which also carries, fast thereon, the finger-wheel 20 and the line-spacing gear 21.

A card 22, upon which it is desired to 105 type a line of data, such as is indicated by the numeral 23, may be placed at the front of the platen in a position to be struck by

a type-bar 24. The card is inserted bottom edge first between the platen and clips 25, and is lowered down to a stop 26.

Then, a line is typed upon the card and 5 the card is withdrawn and another fresh card inserted, and so on. After typing each card, the copy-sheet and the carbon-sheet are simultaneously line-spaced around the platen, either by operating the finger-wheel 10 20 or the regular line-spacing mechanism (not shown) to expose an unused portion of the sheets.

One of the features of this invention is 15 that the clips may be readily slipped onto and off from the machine, and to this end the clips are provided with a supporting or lower member having a loop 27, partly open, so that it may be sprung over the feed-roll shaft 28 and slid thereon for lateral 20 adjustment. From the loop, downwardly and forming an integral part thereof, there is provided a fork-like extension 29 which terminates in two prongs 30 bearing upon a shaft 31, which normally is used to release the feed-rolls by means of a link 32 operating upon a crank 33. Upwardly extending from the lower member and fast thereto, there is provided a resilient metal strip 34 which is normally held under tension 30 35 against the platen holding the card 22 thereinbetween. Said strip 34 is shown in the drawings soldered at 35 to the loop 27, but it is obvious that the two members may be made out of one piece without departing from the spirit of the invention.

Referring more particularly to Figure 3, it will be noted that the clips are inwardly bent when off the machine, as shown in full lines in said Figure 3, while when placed 40 in the machine the clips are under tension between the shaft 31 and the platen, as indicated in dot-and-dash lines.

The card is squared by forcing its lower edge 36 against the loop 27, which forms 45 a locating stop for the card. Due to the fact that the clips are not adjustable and the stop formed by the loop 27 is at a fixed position relatively to the printing line on the platen, the card 22 must consequently 50 be designed to be adaptable to this condition, so that the line of typing will be a distance from the bottom edge 36 equal to the distance between the loop 27 and the printing line on the platen.

Referring to Figure 1, it will be noted 55 that the carbon-sheet interposing the card and the copy-sheet underlies the card only and not the stub 37 which is separable from the card at the perforated line 38. The carbon-sheet extends from the left-hand edge of the copy-sheet to the line 38, so that the total 39 on the stub 37 may be typed thereon 60 but not transferred to the copy-sheet, upon which it is desired to copy one total only 65 indicated by the numeral 40.

Variations may be resorted to within the scope of the invention, and portions of the improvements may be used without others.

Having thus described my invention, I 70

1. The combination, in a typewriting machine having a revoluble platen, of upstanding paper-fingers attenuated to about the width of a letter-space and placed between the printed columns of a work-piece to hold the work-piece between its ends against the platen, and means below the printing line supporting said paper-fingers by their bottom ends, said paper-fingers having means effective to position said work-piece in line-space direction. 75 80

2. The combination, in a typewriting machine, of a revoluble platen, feed-rolls rotatably mounted upon a supporting shaft underlying the platen, intercolumnar supporting fingers attenuated to about the width of a letter-space, said fingers being slidably mounted upon said supporting shaft and tangent to the platen at the printing line in a manner to hold a work-piece against the platen, and bottom-edge gages for positioning the work-piece in line-space direction. 85 90 95

3. In a typewriting machine having a platen and a feed-roll shaft underlying the same, a set of inter-columnar attenuated clips tangent to the platen at the printing line, said clips being effective for holding an upstanding card in front of said platen, and tabs struck out of said clips for squaring and locating said card in line-space direction, said clips being detachably mounted upon the feed-roll shaft. 100 105

4. In a typewriting machine having a platen and a feed-roll shaft under the platen, a set of clips tangentially disposed in front of the platen and movable along the length of the platen, said clips being effective to hold a work-piece against the platen at the printing line, and bottom-edge gages, forming an integral part of said clips, for locating the card in line-space direction. 110 115 120

5. In a typewriting machine including a platen and a feed-roll mechanism having a plurality of rolls revolvably mounted upon a shaft under the platen, a set of clips tangentially disposed in front of the platen for effectively holding a card flat against the platen, said clips having means for locating the card, and means whereby the clips may be temporarily fastened to the shaft upon which the feed-rolls are mounted, said last-mentioned means comprising a loop forming an integral part of the clips and encircling the shaft and a downwardly-extending fork-like supporting member bearing against another shaft in the machine to hold the clips under tension against the platen. 125 130

6. In a typewriting machine having a platen and two rods in proximity thereto

- and below the printing line on the platen, a plurality of resilient paper clips detachably and slidably mounted upon one of the rods for holding and locating a card adjustably to said platen in upstanding, flat position, said clips having a downwardly-extending fork-like piece bearing against the other rod for effectively holding the clips under tension against the platen.
- 5 7. In a typewriting machine having a platen and two rods in proximity and parallel thereto and below the printing line on the platen, a plurality of clips of resilient material slidably and detachably mounted
- upon the rod nearest to the printing line on the platen, said clips comprising a lower or supporting member and an upper or card holding member, the supporting member comprising an open loop encircling the rod nearest to the printing line and having two fingers extending downwardly from said loop and bearing upon the other rod, and the upper member comprising a comparatively narrow strip fast to the lower member on the loop and extending upwardly tangentially to the platen and bearing upon it to hold a card thereinbetween.
